Patented Sept. 26, 1967

208,718

CONDIMENT SHAKER

Mel Appel, 9 Nottingham Road, Livingston, N.J. 07039, and Martin Schnur, St. Cloud One, West Orange, N.J.
07052

Filed Nov. 23, 1966, Ser. No. 4,793

Term of patent 14 years

(Cl. D44—22)

The dominant features of our design reside in the portions shown in solid lines on the drawings.

We claim:

The ornamental design for a condiment shaker, as shown and described.
